ATTORNEY

UNITED STATES PATENT OFFICE

WILLIAM L. ROWLAND, OF MOSIER, OREGON

VALVE TAPPET ADJUSTING TOOL

Application filed April 17, 1929. Serial No. 355,850.

This invention relates generally to internal combustion engines, and particularly to tools for adjusting the valve tappets thereof.

5 The main object of this invention is to provide an exceedingly simple and efficient form of valve tappet adjusting tool whereby a setting or adjustment can be quickly and accurately made by an unskilled person without 55 out the use of a thickness gage of any kind.

The second object is to enable the mechanic to detect audibly the number of thousandths of clearance he is providing in each instance.

15 These, and other objects, will become more apparent from the specification following as illustrated in the accompanying drawings, in which:

Figure 1 is a plan of the device.

20 Figure 2 is a section taken along the line 2—2 in Figure 1.

Figure 3 is a section taken along the line 3—3 in Figure 2.

Figure 4 is a fragmentary section through 25 the valve and its operating mechanism showing the tool in position for adjustment.

Figure 5 is a section taken along the line 5—5 in Figure 4.

Similar numbers of reference refer to 30 similar parts throughout the several views.

Referring in detail to the drawings, in order to illustrate this invention there is shown a common form of valve 10 normally resting against a seat 11 by a valve spring 12. There is also shown a cam 13 which en- 35 gages a head 14 of a valve tappet 15 pro- provided with flattened sides 16. In the valve tappet 15 is mounted an adjusting screw 17 whose head 18 is separated from the tip 19 of the valve stem 20 by a clearance space 21 which, as is well known, should be accurately 40 adjusted, since if it is too small the valves will not seat properly when heated, and if it is too large the tappets will be unduly noisy. A satisfactory adjustment, there- 45 fore, is a precision operation and is normally performed by trial and a subsequent gag- ing by means of thickness or feeler gages.

It is well understood by the skilled me- 50 chanic that the personal equation enters into

the use of these gages, and in addition to this fact uneven wearing of the tip 19 and its associated screw head 18, often results in an inaccurate and unsatisfactory adjustment of the valve, usually in the way of over-clearness.

There is also shown a lock nut 22 which is loosened or tightened, as the case may be, by means of an ordinary end wrench 23.

Referring more particularly to the device 60 it will be seen to consist of an adjusting handle 24 and a holding handle 25 which are hingedly joined near the middle thereof by means of a pin 26 which passes through the ears 27 and 28. The adjusting end 29 of 65 the handle 24 is provided with a circular recess 30 which terminates in the cutaway ends 31 which are preferably radial with the recess 30.

70 Journaled in the recess 30 is a gear 32 having a hub 33 formed on each side thereof, which hub occupies the recess 30. The gear 32 is provided with a slot 34 adapted to receive the head 18 of the screw 17. Meshing with the gear 32 are the pinions 35 which are 75 two in number in order to maintain a driving relation with the gear 32 while one of the pinions 35 is crossing the gap in the gear teeth formed by the slot 34. The pinions 35 have short projecting pivots 36 formed of each of 80 which journals in the handle 24.

Also journaling in the handle 24, and meshing with both pinions 35, is a driving gear 37 rotatably mounted on the pivot 37—A which gear is held in position by a spring 85 pawl 38 which will enable the gear 37 to be turned in either direction by hand, and of a nature which will cause a sharp clicking sound as the pawl rides over the teeth. The ratio between the gears 32 and 37 and the relation of this ratio to the pitch or lead of the screw 17 is such as to bring about an adjustment of .001 of an inch at the head 18 when the pawl 38 has clicked over one tooth on the gear 37. 95

In order to further support and retain the gears 32 and 37 and the pinions 35 there is provided an arm 39 which is similar in shape to the adjusting end of the handle 24 and is secured thereto by means of the screws 40. 100

The holding handle 25 is provided with a 5
slidable wrench end 41 which may be held
in any desired position by means of the thumb
nut 42 on the screw 43. The ends 44 of the
handles 24 and 25 are urged together by
means of a spring 45 and are limited in their
movement toward each other by means of a
screw 46, one end of which is fastened to a
handle 44 and the other end of which passes
loosely through the opposite handle and
which carries thereon between the handle
ends 44 an adjusting nut 47.

The operation of the device is as follows: 10
The gear 37 is first rotated by hand so that
the gear 32 will be caused to move with its
slot 34 registering with the open ends 31.
The wrench 41 is now in a retracted position
(as shown in full lines in Figure 2). The
adjusting end of the handle 24 is then slipped
20 upon the head 18 of the screw 17. The gear
37 is then turned until the straight sides 16
of the valve tappet 15 are in position to re-
ceive the wrench 41, which is then moved into
position to hold the valve tappet 15 and
30 clamped there by means of the thumb nut 42.
The lock nut 22 is now loosened by means of
the wrench 23 and the screw 17 rotated by
turning the gear 37 with the fingers until the
head 18 comes into engagement with the tip
39 of the valve stem 20.

If, for example, it is now desired to pro- 35
vide .004 of an inch clearance it is only
necessary to rotate the gear 37 in the opposite
direction until four clicks are heard from
the pawl 38. The nut 22 is now tightened by
means of the wrench 23 and the tool removed
from the tappet which now has .004 of an inch
clearance. In other words, each click from
the pawl 38, after the head 18 is brought into
40 engagement with the tip 19, represents an ad-
ditional thousandths of an inch of clearance.
Obviously, any other value or sub-division
thereof could be employed without departing
from the spirit of this invention.

The reason for making the handle 25 hinged 45
(as shown) is to make it possible to vary the
distance between the adjusting end and the
holding end of the tool to enable it to adapt
itself to different spacings between the head
50 18 and the flattened spaces 16. While there
is very little difference in the adjusting screws
17 in various types of motors, any difference
therein would be compensated for by provid-
ing a variety of wrench sizes 41 as well as
55 appropriate sizes of openings or slots 34 for
the head 18.

It is obvious that while a sound producing 60
pawl 38 is employed for the reason that valve
adjustments are often made in a poor light,
it is also possible to calibrate the moving parts
in the adjusting member in order that the
amount of adjustment can be read directly
65 in any desired units of measure.

I claim:

65 1. A valve tappet adjusting tool having

in combination a frame, a rotatable segment
gear mounted in said frame constituting an
open end wrench, a pair of pinions meshing
with said gear, a drive gear meshing with
both of said pinions, a rotatable holding 70
wrench hingedly mounted on said frame, and
means for varying the spacing between said
wrenches along the axis of the tappet.

2. A valve tappet adjusting tool consisting
of a pair of open ended wrenches, one of said
wrenches having a rotatable head for engag- 75
ing the tappet adjusting screw and the other
wrench having a sliding head adapted to en-
gage the valve tappet and hold same against
rotation, said rotatable head consisting of a 80
segment gear having two pinions meshing
therewith adapted to bridge the opening
therein, and having a gear for driving both
of said pinions simultaneously for the pur-
pose of maintaining a continuous drive for 85
said rotatable head regardless of its position.
